[57] **CLAIM**

The ornamental design for a compact disk case, as shown and described.

DESCRIPTION

FIG. 1 sets forth a perspective view of a compact disk case showing the present invention new design in its closed position;

FIG. 2 is a rear view thereof;

FIG. 3 is a top view thereof;

FIG. 4 is a front view thereof;

FIG. 5 is a left side view thereof with the right side being a mirror image thereof;

FIG. 6 is a bottom view thereof;

FIG. 7 is a perspective view thereof in its open position; and, FIG. 8 is a perspective view of an alternate embodiment of the design shown in FIG. 1; the sides not showing being substantially similar to the first embodiment except for the inwardly tapered sides.
